UNITED STATES PATENT OFFICE

2,055,301

FRACTIONATION COLUMN EQUIPMENT

Elliott B. McConnell, Cleveland Heights, Ohio

Application December 10, 1934, Serial No. 756,844

3 Claims. (Cl. 261—114)

In my Patent No. 1,865,400 there is set forth a construction making possible the trapping out of a stream from any given plate of a fractionating column without disturbing the relative conditions. My present invention provides an improvement on this construction.

In the construction referred to in said patent two openings are provided in one or more plates of a fractionating column and one of these openings leads to the plate below while the other leads to a draw off. The object of the invention in both instances is to trap out a portion of the material on one plate without disturbing relative conditions and this is sought to be accomplished in the patented construction by providing a sliding closure member, common to both openings, which proportionately varies the cross sectional area of the openings. In the present application the object is to vary the extent of periphery of the two openings, that is, while one periphery is increasing the other periphery is decreasing in direct proportion at all times. In the patented construction while the cross sectional area of one opening is increasing the cross sectional area of the other opening is decreasing in proportion, but the peripheral extent of each opening does not vary in proportion at all times.

To the accomplishment of the foregoing and related ends, the invention, then, comprises the features hereinafter fully described, and particularly pointed out in the claims, the following description and the annexed drawing setting forth in detail certain illustrative embodiments of the invention, these being indicative however, of but a few of the various ways in which the principle of the invention may be employed.

In said annexed drawing:—

Fig. 1 is a schematic side elevation, partly broken, of a fractionating column in accordance with the invention; Fig. 2 is a sectional view, on enlarged scale, taken on a plane indicated by the line II—II, Fig. 1; Fig. 3 is a detail sectional view taken on a plane indicated by the line III—III, Fig. 2; Fig. 4 is a section taken on a plane indicated by the line IV—IV, Fig. 2; and Fig. 5 is a view corresponding to Fig. 2, showing a modification.

The fractionating column in general may be of any desired design and construction providing plates, and may comprise a column shell 2, with inlet 3 and outlet 4, and plates 5 in number as desired. The plates have constant level overflows 6, and means of any convenient form for diverting the rising vapor under the liquid, for example bell caps 7 of any usual or preferred detail. On

the plate also is an overflow 8 leading to the plate below, and adjacent such overflow or opening is another overflow or opening 9 leading to a point without the column, for instance by a conduit 10. A regulable or openable and closable control for the adjacent overflows is arranged, as in the form of a slide 11 guided in suitable guideways such as guides 12. A control rod 13 with any convenient operating means, such as a handle 14, extends through the column-shell 2 to a point outside for allowing manipulation and setting to the desired point. A stuffing box 15 may be provided to prevent leakage around the rod. By the arrangement of graduations 16 on the rod, in convenient scale of percentage or dimension as desired, the set or position of the slide may be easily indicated on the outside. An additional guide 20 may be provided for the rod 13 with advantage. A weir or level 17 is desirably positioned between the trap-out and the bells. In its detail construction, the slide 11, as indicated in Fig. 2, is provided with a notched edge 18, 19, for each of the adjacent openings 8, 9, such notches being of curved form, and providing incremental proportional increase and decrease of the adjoining openings as the slide is moved in one direction, and vice versa. As a further refinement the curves of notch outline may be laid out on a sweep of paraboloid form. The ends of the openings 8, 9, may also be of a paraboloid form. In the form shown in Fig. 5, the notched edges 18', 19', instead of being curved, are laid on straight lines, the slide again affecting a proportioned opening of one overflow and closing the other, or vice versa, as moved.

The liquid passing through the openings in the fractionating plate does not flow as a solid stream of the cross sectional area of the opening, but seeps over the periphery of the opening, being influenced by capillarity, and the flow for each opening is thus proportional to the periphery presented for overflow.

Any of the plates of the column as preferred may be provided with such trap-out regulator means, and in a fractionating column operating on distillate vapors which are of mixed character, such as for instance in the case of petroleum, will thus permit obtaining accurate side streams at any plate desired. The control 11 may be set by handle 14, proportioning the amount of opening 50 and closure between the adjacent overflows down to the next plate and outside, as desired in any given instance, the gauge 16 serving to indicate the position.

Other modes of applying the principle may be 55

employed, change being made as regards the details described, provided the means stated in any of the following claims, or the equivalent of such, be employed.

5 I therefore particularly point out and distinctly claim as my invention:—

1. In a device of the character described, a closed shell, a substantially horizontal plate therein having an opening at overflow level, a 10 second opening adjacent thereto, a conduit leading from said last mentioned opening to a point outside said shell, and a regulable closure member, in common for said openings for simultaneously closing one opening and opening the other, 15 said openings and closure member being so shaped and positioned that said member causes the peripheral extent of one to increase in direct proportion to the decrease of the peripheral extent of the other, said closure member having a 20 notched edge for each opening.

2. In a device of the character described, a closed shell, a substantially horizontal plate therein having an opening at overflow level, a second opening adjacent thereto, a conduit leading 25 from said last mentioned opening to a point outside said shell, and a regulable closure mem-

ber, in common for said openings for simultaneously closing one opening and opening the other, said openings and closure member being so shaped and positioned that said member causes the peripheral extent of one to increase in direct proportion to the decrease of the peripheral extent of the other, said closure member having a 5 curved notched edge for each opening.

3. In a device of the character described, a closed shell, a substantially horizontal plate 10 therein having an opening at overflow level, a second opening adjacent thereto, a conduit leading from said last mentioned opening to a point outside said shell, and a regulable closure member, in common for said openings for simultaneously closing one opening and opening the other, 15 said openings and closure member being so shaped and positioned that said member causes the peripheral extent of one to increase in direct proportion to the decrease of the peripheral extent of the other, said closure member having a 20 curved notched edge for each opening, laid out on a sweep of paraboloid form, and said openings having their contours in a paraboloid form. 25

ELLIOTT B. McCONNELL.

CERTIFICATE OF CORRECTION.

September 22, 1936.

Patent No. 2,055,301.

ELLIOTT B. McCONNELL.

It is hereby certified that the above numbered patent was erroneously issued to the inventor said "McConnell", whereas said patent should have been issued to The Standard Oil Company (Ohio), Cleveland, Ohio, a corporation of Ohio, as assignee of the entire interest in said invention as shown by the records of assignments in this office; and that the said Letters Patent should be read with this correction therein that the same may conform to the record of the case in the Patent Office.

Signed and sealed this 1st day of December, A. D. 1936.

Henry Van Arsdale

Acting Commissioner of Patents.
